GEORGE E. BAKER, OF SCPIOVILLE, NEW YORK.

DRAFT-REGULATING DEVICE.

1,116,534.

Specification of Letters Patent.

Patented Nov. 10, 1914.

Application filed March 12, 1912. Serial No. 683,271.

To all whom it may concern:

Be it known that I, GEORGE E. BAKER, of Scipioville, in the county of Cayuga and State of New York, have invented a new and useful Draft-Regulating Device, of which the following is a specification.

This invention has for its object the production of a thermostatic draft regulating device which is particularly simple in construction, and highly efficient and durable in use; and it consists in the combinations and constructions hereinafter set forth and claimed.

In describing this invention reference is had to the accompanying drawings in which like characters designate corresponding parts in all the views.

Figures 1 and 2 are elevations of one embodiment of my invention, parts thereof being shown in their position occupied when the draft controller, as a damper, is open in Fig. 1, and is closed in Fig. 2. Fig. 3 is a sectional view of parts seen in Figs. 1 and 2.

This draft regulating device comprises a draft controller, means tending to normally actuate the controller to open or close the same, an escapement comprising a detent for normally preventing actuation of the controller by said means, and operating to permit sufficient movement thereof for the controller to move from its closed to its open position or vice versa, a thermostat, and mechanical means operated by the thermostat for operating the detent.

I have here illustrated my invention as constructed to open and close the damper of a pipe and as carried by the pipe.

1 is the pipe which may be a stove pipe or the smoke pipe of a furnace or other heater.

2 is the controller as a damper in the pipe, the damper being here shown as movable about an axis and mounted on a rotatable member as a rod 3 extending transversely through the pipe and projecting beyond opposite sides thereof.

4 is a weight having a flexible member as a chain 5 adapted to be wound by hand on one projecting end of the rod 3, the rod being provided at its other end with a handle 6 by which the rod and damper can be turned to wind the chain 5 on the rod, said weight and chain constituting one form of means tending to normally actuate the controller. The chain 5 is connected to the rod 3 by means of a member 7 mounted on the rod and so positioned that when the chain

is entirely unwound the weight will exert force on the member 7 in the direction tending to close the damper 2.

8 is a detent forming part of the escapement, said detent being here shown in the form of an angle lever pivoted at 9 at its angle and having surfaces 10 and 11 at the ends of such arms arranged in the path of the escapement arms 12 mounted on the rod 3 near the handle 6, the surfaces 10 and 11 being arranged to alternately engage one of the arms 12 so that when one of the arms 12 is engaged with the surface 10 of the detent 8, the damper will be closed and when arranged with the surface 11, the damper will be open. The detent is also formed with a ratchet surface 13 in advance of the surface 11 for permitting the rod to be rotated by hand in a reverse direction to wind up the chain 5.

The arms 12 are preferably formed on a member 14 adjustably mounted on the rod 3 and held in position by means as a set screw 15. The member 14 can be adjusted on the rod 3 to change the angle of the arms 12 with respect to the damper 2. The detent is pivoted to a suitable lug 16, Fig. 3, provided on a base plate 17 which may be secured to the pipe 1 or other support in any suitable manner.

18 is a thermostat here shown as mounted on the pipe 1 and provided with means for reacting directly with the detent 8 whereby the movement of the thermostat due to the unequal expansion and contraction of the metals thereof, is transmitted to the detent to actuate the same.

In the illustrated embodiment of my invention, the thermostat comprises two sections 19, 20, each of which is here shown as composed of two elongated strips of different metals as iron and zinc, the strips being bent in the form of channel iron, and the strips of the section 19 or 20 being fixed together at corresponding ends, as their upper ends, by means as screws 21, and having their lower ends spaced apart and secured to opposite sides of a block 22 or 23, the block 22 to which the strips of the section 19 are secured being pivoted at 24 to a base plate 25 secured to the pipe 1, and the block 23 to which the strips of the section 20 are secured being carried by and fixed to the block 22, so that during movement of the pivoted block 22 about its pivot 24, the block 23 will have movement about the axis 24.

which movement is magnified at the end of the section 20. The pivotal movement of the block 22 is due to the unequal expansion and contraction of the strips of the section 19 fixed to such pivoted block, which section is fixed to a lug 26 on the base plate 16, and hence the section 20 connected to the block 22, has an amplified movement due to the unequal expansion and contraction of the strips thereof and to the movement of the block 22 about the pivot 24. If desired the section 20 may be composed of an arm or strip having no thermostatic qualities, and merely serving to magnify and transmit the movement of the section 19.

The amplified motion of the free end of the section 20 is, in the illustrated embodiment of my invention, shown as transmitted to the detent 8 by means carried by the section 20 and movable therewith and coacting directly with the detent. Said means is here shown as a spring tongue 27 fixed to the free end of the section 20 and having means for entering a slot 28 in the detent 8, the spring arm being provided with an adjusting means as a set screw 29 threading through a nut 30 associated with said tongue 27, the screw 29 bearing against the section 20 either directly or through the base of said tongue 27.

The means extending into the slot 28 is a member 31 preferably adjustable for varying the starting position of the detent 8 and thus rendering the control more or less sensitive as desired, said member 31 being here shown as pivoted at 32 to the tongue 27 and having an inclined or cam portion 33 movable in the slot 28, the member 31 being adjustable about its pivot for bringing different portions of the inclined or cam part 33 thereof into the slot 28 and thus changing the position of the detent 8 on its axis.

Movement of the member 31 in one direction on its axis causes the detent to move the surface 10 farther under the arm 12 thus requiring a greater movement or contraction of the thermostat to move said surface 10 out of engagement with the arm 12 and permit the damper to move from the position shown in Fig. 2 to that shown in Fig. 1. Such movement of the member 31 carrying the surface 10 farther under the arm 12, also moves the surface 11 farther out of the path of such arm 12 so that a small expansion of the thermostat will disengage the surface 11 of the detent 8 and the arm 12 and permit the damper to close.

Movement of the member 31 in the opposite direction on its pivot causes the surface 11 to be shifted farther into the path of the arm 12 and the surface 10 farther out of the path of said arm so that a slight contraction of the thermostat will cause the damper to be open and a greater expansion

of the thermostat will be required to move the surface 11 out of the path of the arm 12. The thermostat may be wholly disconnected from the detent by shifting the member 31 a sufficient distance to carry the cam portion 33 entirely out of engagement with the walls of the slot 28. I have also provided this invention with means by which the damper can be locked in its closed position, said means comprising a pivoted lever 34 here shown as mounted on the pivot 9 of the detent 8 and is movable on its pivot into position so that the shoulder 35 thereon will underlie the arm 12 and hold the arm 12 from movement irrespective of any action of the thermostat.

My regulating device is particularly advantageous in that it can be easily applied, and can be applied to stoves and other heaters used in connection with incubators.

85

What I claim is:

1. In a draft regulating device, the combination of a pipe, a damper in the pipe, means tending to actuate the damper, an escapement comprising a detent located on the outside of the pipe near the damper for normally preventing actuation thereof by said means, a thermostat mounted on the outside of the pipe and supported by the pipe, and mechanical means carried by the thermostat and having a variable connection with the detent for transmitting the movement of the thermostat to the detent, substantially as and for the purpose set forth.

2. In a draft regulating device, the combination of a draft controller movable about an axis, means tending to actuate the controller about its axis, an arm movable about the axis and connected to the controller, a detent for coacting with the arm, the detent being in the form of an angle lever pivoted at its angle and having means at its opposite ends for alternately coacting with said arm, and a thermostat for controlling the operation of the detent, substantially as and for the purpose specified.

3. In a draft regulating device, the combination of a draft controller, means tending to actuate the controller, an escapement mechanism comprising a pivoted detent normally preventing movement of the regulator, a thermostat for actuating the detent, and means carried by the thermostat and coacting directly with the detent for transmitting the movement of the thermostat to the detent, said means comprising a member adjustable for shifting the detent on its pivot thereby changing the normal or starting position of the detent, substantially as and for the purpose set forth.

4. In a draft regulating device, the combination of a draft controller, means tending to actuate the draft controller, an escapement for controlling the operation thereof

110

115

120

125

130

by said means, the escapement comprising a 5
detent in the form of an angle lever pivoted
at its angle, the arms of the lever being pro-
vided with stop faces, one of which is in
operative position when the other is out of
5
operative position, a thermostat, means car-
ried by and movable with the thermostat
and coacting directly with the detent, the
detent being provided with a slot and said
10
means including an inclined part arranged
in the slot and movable about an axis for
carrying different portions of its inclined
part into the slot and thereby shifting the
detent on its pivot to change the normal or
15
starting position thereof, substantially as
and for the purpose described.

5. In a draft regulating device, the com-
bination of a draft controller, means tend-
ing to actuate the controller, an escapement
20
for controlling the actuation of the con-
troller by said means, the escapement com-
prising a pivoted detent normally prevent-
ing movement of the regulator, a thermostat,
and means carried by the thermostat and co-
25
acting directly with the detent for transmit-
ting the movement of the thermostat to the
detent, said means comprising a member
shiftable into and out of engagement with
the detent for connecting and disconnecting
30
the detent from the thermostat, substantially
as and for the purpose specified.

6. In a draft regulating device, the com-
bination of a draft controller, means tend-
ing to actuate the draft controller, a thermostat
35
for controlling the operation of the control-
ler by said means, the thermostat comprising
a section composed of strips of different
metal, said strips being fixed together and
held from relative movement at correspond-
40
ing ends, and spaced and fixed at their other
ends, and means at the latter ends for re-
ceiving, transmitting and magnifying the
relative movement of said strips, substan-
tially as and for the purpose set forth.

45
7. In a draft regulating device, the com-
bination of a draft controller, means tend-
ing to actuate the controller, a thermostat for
controlling the operation of the controller
by said means, the thermostat comprising
50
two sections, each formed of strips of differ-
ent metal fixed together at corresponding
ends, a metal block interposed between and
fixed to the other ends of the strips of each
section, the blocks of both sections being rig-
55
idly secured together and one block being
pivoted and the strips associated with the
pivoted block being fixed from movement

relatively to the pivoted block at the ends
thereof which are fixed together and the
ends of the strips associated with the unpiv-
60
oted block being free, and means operated
by the section secured to the unpivoted block
for transmitting the movement of the ther-
mostat, substantially as and for the purpose
described.

8. In a draft regulating device, the com-
bination of a draft controller, means tending
to normally actuate the controller, an escape-
ment comprising a pivoted detent for nor-
mally preventing the actuation of the con-
70
troller by said means, a thermostat, mechani-
cal power-transmitting means between the
thermostat and the detent for operating the
detent, and a pivoted locking device mount-
ed on the pivot of the detent and movable
75
into position to hold the controller from
actuation irrespective of the operation of the
detent by the thermostat, substantially as and
for the purpose set forth.

9. A temperature regulating device com-
prising a draft controller having means
tending to actuate the same, an escapement
member for controlling the actuation of said
controller by said means, a thermostat, an
85
arm mounted on the thermostat and coacting
with the escapement to transmit the move-
ment of the thermostat to the escapement
member, means for adjusting the position of
the arm, and an adjusting lever carried by
90
said arm and movable in a direction at an
angle to the adjusting movement of said
arm, and having a cam coacting with the
escapement member to change the starting
position thereof, substantially as and for the
95
purpose specified.

10. In a temperature regulating device, a
draft controller, means tending to actuate
the controller in one direction, an escape-
ment for controlling the operation of the
controller by said means including two mem-
bers, one an escapement lever for controlling
100
the operation of the other member, and a
lock for coacting with said member and pre-
venting the operation thereof, substantially
as and for the purpose set forth.

In testimony whereof, I have hereunto
signed my name in the presence of two attest-
ing witnesses, at Aurora, in the county of
Cayuga, and State of New York, this 24th
day of February 1912.

GEORGE E. BAKER.
